UNITED STATES PATENT OFFICE.

JOHN MARCZI, OF LA BELLE, PENNSYLVANIA.

BOLTLESS RAIL-JOINT.

1,107,433.

Specification of Letters Patent. Patented Aug. 18, 1914.

Application filed May 27, 1914. Serial No. 841,274.

To all whom it may concern:

Be it known that I, JOHN MARCZI, a subject of the King of Hungary, residing at La Belle, in the county of Fayette and State 5 of Pennsylvania, have invented certain new and useful Improvements in Boltless Rail-Joints, of which the following is a specification.

This invention relates to certain new and 10 useful improvements in boltless rail joints.

An object of the invention is to provide a coupling for the meeting ends of rails, which coupling is mounted on the rails without the use of bolts or detachable fastening 15 means, such a coupling rendering the joint practically rigid with no danger of any of the parts working loose.

A further object of the invention is to 20 provide a fish plate for rail joints adapted to effectively hold the meeting ends of the rails in juxtaposition without the use of bolts or other detachable fastening means.

With the above general objects in view 25 and others that will appear as the nature of the invention is better understood, the same consists in the novel construction, combination and arrangement of the parts to be hereinafter more fully described and then claimed.

30 In the accompanying drawing which shows the preferred embodiment of my invention and to which reference is had herein by like characters designating corresponding parts throughout the several views:—
35 Figure 1 is a side elevational view of a portion of the meeting ends of rails with my invention applied thereto. Fig. 2 is a horizontal sectional view of the same, and Figs. 3 and 4 are perspective views of the fish plates for holding the meeting ends of the 40 rails in locked position.

Briefly described, the present invention embodies the idea of securing together the meeting ends of rails without the use of 45 bolts and nuts and consists of a pair of fish plates disposed at opposite sides of the rail with one of the plates extending through the said rails and operating in connection with the other plate to be held in such position.

50 Referring more in detail to the accompanying drawing, the reference numeral 10 designates a rail of the usual type embodying base flanges, a web, and a head or tread surface. The contacting ends of the rails 10 are preferably of a plane surface as shown 55 in Figs. 1 and 2 so that the meeting ends

may lie juxtaposed. At points equally spaced outwardly from the meeting ends of the rails 10, the webs of the rails are provided with openings 11.

The mechanism for holding the rails 10 in juxtaposition consists of an angle plate comprising the main body part 12 lying in contact with the webs of the rails 10 and of a height to engage the overlying head and base flange of the rail with the angular projections 13 extending through the openings 11. These angular projections 13 carry extension locking plates 14 which are hinged thereto as at 15. Secured as at 17 to the outer faces of the angle extensions 13 are flat leaf springs 18 freely engaging at their outer ends the hinged locking plates 14. The locking plates 14 are provided with cut out portions 19 for the insertion of a suitable tool or the hand to cause the same to assume the position shown in dotted lines in Fig. 2. In passing the angle extensions 13 and the locking plates 14 through the openings 11 in the webs of the rails 10 the said 75 extending parts are caused to pass through openings 20 provided in the fish plate 21 disposed at the opposite side of the rail webs to the member 12 and lying in contact with the webs. When the locking plates 14 have been passed through the registering 80 openings 11 and 20 as shown in the dotted line position in Fig. 2, the spring 18 will cause the locking plate 14 to be moved to a position to engage the fish plate 21 as shown 90 in Fig. 2 and prevent the removal thereof.

The operation of the device is believed to be clearly evident from the above description and showing, but it will be noted that the meeting ends of the rails 10 are effectively held in locked position by the fish plates 12 and 21, the locking plate 14 carried by the fish plate 12 caused by its spring 18 to engage the fish plate 21. When it is desired to remove the fish plates from the 100 rails 10 it is only necessary to place a suitable tool in the opening 19 in the locking plate 14 and bring the same in the position shown in dotted lines in Fig. 2, after which the fish plate 12 may be readily removed 105 from the rails.

While I have shown and described the preferred embodiment of my invention, I do not wish to confine myself to the exact details of construction shown, as various 110 forms, modifications and arrangements of the parts may be had without departing

from the spirit and scope of the invention as claimed.

What I claim as new is:—

1. In a rail joint, a pair of rails having their meeting ends contacting and provided with openings in the webs equidistantly spaced from the joint, a fish plate provided with angular arms extending through said opening, a plate provided with openings 10 registering with the openings in the rail web disposed at the opposite sides of the rails, the fish plate extensions extending therethrough and spring-pressed locking plates carried by said extensions and adapted in locking position to engage the outer face of the locking plate.
2. In a fish plate for rail joints, a body portion, right angular extensions carried by said body portion, locking plates hinged to 20 the extensions, and leaf springs carried by the extensions and having their free ends

engaging the locking plates to cause the same to move inwardly.

3. In a rail joint, a pair of meeting rails, an opening provided in the web of each rail, 25 a plate mounted at one side of the webs and provided with openings registering with the web openings, a locking fish plate disposed at the opposite side of the rail webs, angular extensions carried by the locking fish 30 plate and extending through the registering openings, a locking plate hinged to each of the angular extensions, and a spring carried by each of the angular extensions and engaging the locking plates to cause the 35 same to lie in contact with the plate.

In testimony whereof I affix my signature in presence of two witnesses.

JOHN MARCZI.
